ELECTRIC HAIR CURLER

Samuel L. McNair, Overland Park, Kans., assignor to
Dazey Products Co., Kansas City, Mo.

Filed Feb. 26, 1974, Ser. No. 445,962

Term of patent 14 years

Int. Cl. D28—03

U.S. Cl. D86—10 E

Fig. 1.

Fig. 2.

Fig. 3.

Fig. 4.

Fig. 5.

Fig. 6.

FIG. 1 is a front perspective view of an electric hair curler showing my new design;

FIG. 2 is a side elevational view of same, the other side being substantially the same in appearance;

FIG. 3 is a top plan view of same;

FIG. 4 is a bottom plan view of same;

FIG. 5 is an end elevational view taken from the right hand end of FIG. 2; and

FIG. 6 is an end elevational view taken from the left hand end of FIG. 2.

I claim:

The ornamental design for an electric hair curler, as shown and described.
